E. C. NICHOLS

GAME

Filed March 17, 1927

UNITED STATES PATENT OFFICE.

EUGENE C. NICHOLS, OF SIOUX FALLS, SOUTH DAKOTA.

GAME.

Application filed March 17, 1927. Serial No. 176,017.

My invention relates to a game, and it is my object to provide apparatus for a game similar to the old game known as "bean bags."

5 A further object of the invention is to provide such a game apparatus which is of simple, durable, and inexpensive construction.

10 A further object is to provide such a game apparatus which may be folded for shipping in such a manner as to be protected against injury.

15 With these and other objects in view, my invention consists in the construction, arrangement and combination of the various parts of my device, whereby the objects contemplated are attained, as hereinafter more fully set forth, pointed out in my claims, and illustrated in the accompanying drawings, in which:

20 Fig. 1 is a perspective view of the game apparatus.

Fig. 2 is a longitudinal, sectional view of the base thereof, the top being shown in its 25 two positions in dotted lines.

Fig. 3 is an end view of the base.

Figs. 4, 5 and 6 are views of bags used in playing the game.

25 The game apparatus comprises a base, referred to generally by the reference character A, and a cover, referred to generally by the reference character B.

30 The base A has the bottom member 10 and the side walls 11, forming a shallow trough. To the rear ends of the side walls 11 are secured vertical posts 12 and triangular-shaped walls 13 are secured to the side walls 11 and posts 12. A rear wall 14 connects the posts 12 and is provided with a semi-circular opening 15. A pair of lugs 16 are secured to the inner sides of the walls 11 and are inclined at their ends as at 17 and spaced from the edges of the walls 13 to form the channelled grooves 18. The lugs 16 project above the edges of the walls 11 as illustrated.

35 The cover member B comprises a flat plate 19 provided with a central opening 20 which may be square or round. Flanges 21 and 22 border the sides and one end of the plate 19. The free ends of the flanges 21 are bevelled as at 23 at such an angle that, when the plate 19 rests against the inclined edges of the walls 13, as shown in Fig. 1, the bevelled ends 23 will register with the upper 55 edges of the side walls 11 and the plate 19 will be allowed to extend to the bottom member 10. The channel grooves 18 receive the side extremities of the plate 19 when it is thus positioned and the projecting rods 16 60 accurately position the flanges 21 with respect to the walls 11.

The cover member B is locked in position by latch hooks 25, pivoted to eyes 26, secured to the rear wall 14, and engaging eyes 65 27 in the cover member B. The hooks are so positioned that removal of the cover member is impossible when the hooks are engaged.

When it is desired to pack the apparatus 70 for shipping, the cover member B is removed from the position shown in Fig. 1 and indicated in Fig. 2 by the light dotted lines and is transferred to the position shown in heavy dotted lines in the same figure. It will be 75 noted that in this position the corners of the flanges 21 will overlap the side walls 13, locking the cover member against lateral movement relative to the base. A triangular shaped notch 28 is provided in each of 80 the side walls 13 to receive the bevelled end edge of the plate 19. Hooks 29, pivoted to screw eyes 30, in the bottom member 10, engage screw eyes 31 in the cover member B in such a way as to maintain the cover member 85 against longitudinal movement and to prevent removal of the engagement with the notches 28. Consequently the cover member will be locked against the side walls 11 by the engagement of the hooks 29 and 90 the edge of the wall 19 and the notches 28.

When thus packed, the flanges 21 will be 95 protected against injury, due to the inverted position of the cover member.

When the apparatus is assembled, the opening 15 provides a means for removing bags from the pocket formed to receive them. The bags are shown in Figs. 4, 5 and 6, respectively, and comprise three bags of increasing sizes and varying colors.

100 In playing the game, the player stands at a distance and tosses the bags toward the cover member B. If the bag goes over the top or side of the cover member over the red line 32, the player loses ten points for the bag shown in Fig. 4, five points for the bag shown in Fig. 5, and one point for the bag shown in Fig. 6. The first bag counts 105

five points, the second counts 10 and the third counts fifteen when it is dropped in the opening.

Some changes may be made in the construction and arrangement of the parts of my invention without departing from the real spirit and purpose of my invention, and it is my intention to cover by my claims, any modified forms of structure or use of mechanical equivalents, which may be reasonably included within their scope.

I claim as my invention:

1. A game comprising a horizontal base, an inclined cover member provided with an opening and a pocket formed behind said cover member and provided with an opening for the removal of bags, said cover member and base being formed as shallow troughs registering with each other.
2. A game apparatus comprising a shallow trough-shaped base, triangular-shaped walls at one end of the base, a cover member adapted to rest against inclined edges of said walls to form a closed pocket and hook fasteners cooperating with the upper end of said cover member to secure it to the triangular-shaped walls.
3. A game apparatus comprising a shallow trough-shaped base, triangular-shaped walls at one end of the base, a cover member adapted to rest against inclined edges of said walls to form a closed pocket and hook fasteners cooperating with the upper end of said cover member to secure it to the

triangular-shaped walls, the base being provided with grooves to receive the lower end of the cover member.

4. A game apparatus comprising a shallow trough-shaped base, triangular-shaped walls secured to the inner sides of the side walls of said base, lugs secured to the inner sides of the side walls of said base, the ends of said lugs being inclined and spaced from the inclined edges of said triangular-shaped walls to form grooves and a cover member adapted to be received in one end of said grooves and to be fastened at its other end to the upper extremities of the triangular-shaped walls.

5. In a game apparatus, a shallow, trough-shaped base, triangular walls secured to the inner faces of the side walls of said base at one end thereof, a cover member comprising a plate, side flanges and an end flange secured thereto, said side flanges being adapted to embrace the triangular-shaped walls when the cover member is placed in a position with its flanges in contact with the side walls of the base, the triangular-shaped walls being provided with notches to receive the end edge of the cover member and means for securing the other end of the cover member to the base.

Signed this 7th day of March, 1927, in the county of Minnehaha and State of South Dakota.

EUGENE C. NICHOLS.
